UNITED STATES PATENT OFFICE.

WILLIAM FRANKLIN PENNER, OF RICHARDSVILLE, KENTUCKY.

METALLIC CROSS-TIE.

SPECIFICATION forming part of Letters Patent No. 606,577, dated June 28, 1898.

Application filed April 8, 1898. Serial No. 676,934. (No model.)

To all whom it may concern:

Be it known that I, WILLIAM FRANKLIN PENNER, a citizen of the United States, residing at Richardsville, in the county of Warren and State of Kentucky, have invented a new and useful Metallic Cross-Tie, of which the following is a specification.

The invention relates to improvements in metallic cross-ties.

10 The object of the present invention is to improve the construction of metallic cross-ties and to provide a simple, inexpensive, and efficient one which will be practically indestructible and which will provide a support 15 for rails as elastic as the ordinary wooden cross-tie.

The invention consists in the construction and novel combination and arrangement of parts, as hereinafter fully described, illustrated in the accompanying drawings, and pointed out in the claims hereto appended.

In the drawings, Figure 1 is a perspective view of a metallic cross-tie constructed in accordance with this invention. Fig. 2 is a longitudinal sectional view of the same. Fig. 3 is a transverse sectional view. Fig. 4 is a detail view illustrating the manner of supporting the rails out of contact with the sides of the metallic cross-tie.

30 Like numerals of reference designate corresponding parts in all the figures of the drawings.

1 designates a metallic cross-tie, comprising a horizontal bottom plate 2, sides 3, and top plates 4 and 5, consisting of central and end sections having their adjacent ends spaced apart to receive rails 6 and recessed to form clamps 7 for engaging the bottom flanges of the rails, whereby the latter are securely fastened to the cross-tie without the use of spikes. The side pieces 3 are provided at their upper and lower edges with outwardly-extending flanges 8 and 9, having horizontal faces to fit the bottom plate and the top plates. The bottom flanges are secured to the bottom plate by rivets 10 or other suitable fastening devices, and the upper flanges are detachably fastened to the top plates by bolts 11. If desired, the central section or plate 4 may be permanently secured to the sides 3; but the side plates 5 of the top are detachable in order to permit

blocks 12 of wood to be removed and renewed when necessary.

The blocks of wood which are arranged beneath the rails form elastic supports for the 55 same and enable the metallic cross-tie to furnish as much elasticity or cushioning effect as the ordinary wooden tie.

The sides 3 are provided at their upper edges with recesses 13 to receive the bottom 60 portions of the rails, and the blocks of wood which are arranged between the sides 3 extend above the bottoms of the recesses and support the rails out of contact with the metallic cross-tie. The blocks of wood are protected by being incased in the metallic cross-tie, so that they do not require to be renewed at very short intervals, and they may be readily taken out when the end sections 5 are removed.

70 The invention has the following advantages: The metallic cross-tie is simple and comparatively inexpensive in construction, it possesses strength and durability, and it is adapted to afford an elastic cushion equal to that afforded by an ordinary wooden cross-tie. The wooden blocks may be replaced at a trifling cost, and by being housed within the cross-tie they will last for a long time. The cross-tie while having all the durability and strength 80 of a metal cross-tie possesses at the same time all the advantages of a wooden cross-tie.

Changes in the form, proportion, and minor details of construction may be resorted to without departing from the spirit or sacrificing any of the advantages of this invention.

75 What I claim is—

1. A device of the class described comprising a bottom plate, sides secured to the bottom plate and provided at their upper edges 90 with recesses adapted to receive rails, the central and end top plates secured to the sides and provided at their adjacent edges with means for engaging the rails, the end plates being removable, and the blocks arranged between the sides and extending above the bottoms of the recesses and adapted to support the rails out of contact with the sides, substantially as described.

2. A device of the class described comprising a bottom plate, sides provided with upper and lower outwardly-extending flanges, se-

cured to the bottom plate and having recesses at their upper edges, the central and end top plates secured to the upper flanges of the sides and forming clamps for engaging the bottoms of rails, and wooden blocks arranged within the tie and extending above the bottoms of the recesses and adapted to support the rails, substantially as described.

In testimony that I claim the foregoing as my own I have hereto affixed my signature in the presence of two witnesses.

WILLIAM FRANKLIN PENNER.

Witnesses:
